UNITED STATES PATENT OFFICE.

LEOPOLD KASSANDER, OF NEW YORK, N. Y., ASSIGNOR TO NATHAN MANUFACTURING COMPANY, OF NEW YORK, N. Y.

BOILER CHECK-VALVE.

No. 846,213.

Specification of Letters Patent.

Patented March 5, 1907.

Application filed November 30, 1906. Serial No. 345,699.

To all whom it may concern:

Be it known that I, LEOPOLD KASSANDER, a citizen of the United States, residing in the city, county, and State of New York, have 5 invented a certain new and useful Improvement in Double Boiler Check-Valves, of which the following is a specification.

The invention relates to boiler check-valves used on locomotives to prevent the 10 backflow of the water from the boiler to the injectors which supply the water to the boiler, and more particularly to such boiler check-valves as are designed to be placed upon the back head of the fire-box of the 15 boiler.

In recent locomotive practice it is customary to provide the locomotive-boiler with two injectors, thus necessitating two boiler-checks, one for each injector, and when, as is 20 very often the case, the injectors as well as the boiler-checks are located at the rear head of the fire-box, owing to limited space, there is considerable difficulty in providing the necessary fittings and intermediate parts. 25 Injectors as a rule are provided at their delivery ends with check-valves contained within the confines of the injector-body, so that if anything should be amiss with the boiler check-valve itself the check-valve in 30 the injector will prevent a backflow of the water from the boiler. In the nature of things this check-valve in the body of the injector must be limited in size and as a rule cannot be as substantial in form and construction as is desirable. When the injector 35 is shut down, the sudden confining of pressure in the pipe between injector and boiler produces the sudden closing of the check-valve in the injector-body with a strong pounding 40 effect, the result being that this small and necessarily weak valve does not wear well and very often breaks, interfering with the proper function of the injector and its very important work of supplying the boiler with 45 the necessary amount of water. When the injector is placed on the back head of the boiler, the reduced distance between injector and boiler still further intensifies the effect of the back pressure upon the check- 50 valve in the injector.

The object of my invention is to overcome all these difficulties by so constructing the boiler-check that it shall be double—that is to say, shall have for each injector a separate

and distinct boiler check-valve by providing 55 in connection with each of said valves an intermediate check-valve of substantial design and also a stop-valve, all contained within a single casting and combined in compact and efficient form and arrangement, 60 with an outlet or discharge which is common to the two lines of supply controlled by the two systems of check-valves.

To enable those skilled in the art to understand my invention, I will now proceed to 65 describe the same in detail in connection with the accompanying drawings, is which—

Figure 1 is a general view, partly in end elevation and partly in vertical section, of a locomotive-cab, showing two injectors and a double boiler check-valve on the back head of the boiler. No structural details are shown, the figure being largely diagrammatic and designed to indicate graphically the limited space in which these instruments must 70 be contained. The remaining figures are drawn on a larger scale and exhibit the structural details of a double boiler-check embodying my invention. Fig. 2 is a vertical section of my improved boiler-check on 75 line 2 2, Fig. 4. Fig. 3 is a vertical section on line 3 3, Fig. 2. Fig. 4 is a horizontal section on line 4 4, Fig. 2. Fig. 5 is a horizontal section on line 5 5, Fig. 3. Fig. 6 is a section 80 of a portion of the valve casing or body on line 6 6, Fig. 3. Fig. 7 is a face elevation of the flange at the boiler end of the delivery-chamber, by which the valve casing or body is attached to the boiler. In all of these 85 Figs. 2-7, inclusive, parts which are not in 90 the line of section are omitted for purposes of clearness.

In Fig. 1, *a a* represent two injectors, and *b* a double boiler-check. It is apparent from this illustration that space is so limited that in most cases no intermediate device external to the boiler-check can be applied between injector and boiler-check in case it should be desired to dispense with the unsatisfactory check-valve in the body of the 95 injector at its delivery end. In my improved double boiler-check, which I shall now proceed to describe in connection with Figs. 2-7, provision is made for the convenient application and use of such devices. 100

c is the body of a double boiler-check, which is internally divided, generally considered, into two completely-separate sec- 105

tions. Each one of these sections is subdivided into a primary chamber *e*, an intermediate chamber *f*, and a check-valve chamber *g*, the valve-body being provided also with a single outlet, preferably in the shape of a delivery-chamber *h*, which is common to the two check-valve chambers *g*. The primary chamber is designed to be in direct communication with the delivery end of its appropriate injector, the latter to be directly attached to the receiving end *i* of said chamber, which is internally threaded for this purpose. Between the primary chamber and intermediate chamber is placed an automatic check-valve *k*, and between the intermediate chamber and check-valve chamber is placed the automatic check-valve *l*. Between each check-valve chamber and the delivery-chamber, which latter, as above said, is common to the two halves of the check-body, is placed a stop-valve *m*, which controls communication between its check-valve chamber and the delivery-chamber.

To secure compactness and efficient arrangement, the two series of chambers are placed side by side in the body or shell of the double check, separated the one series from the other by a vertical partition web or wall *d*, and in each series the three chambers are superposed one on the other, the primary chamber *e* below, the intermediate chamber *f* next, and the check-valve chamber *g* on top.

The valve *l* in the top chamber *g* corresponds to the ordinary boiler check-valve and is of the usual flat-seated gravity type. It is provided with a removable horizontal seat located in an opening in the bottom of the chamber, through which communication is had with the intermediate chamber *f* next below. The valve and seat are accessible through an opening formed in the top of the body and closed by a screw cap or plug *l*², as usual in this class of instruments.

The intermediate valve *k* is of the type known as a "swing-valve." It consists of a bevel-seated valve proper, *k*, provided with a cylindrical stem *k*¹, mounted in an annular bearing-sleeve on the free end of a swinging arm *k*³, wherein it is sustained by a lock-nut *k*² in such manner as to be capable of free axial rotation. The swinging arm *k*³ is pivoted or hinged at *k*⁴ to the interior of the valve-body. The valve *k* seats on a seat *k*⁵, screwed into a partition-wall, which separates chambers *e* and *f*. This seat is removable and renewable whenever occasion should require. The seat and valve are inserted through an opening covered by cap *k*⁶.

By reference to Fig. 3 it will be seen that the seat *k*⁵ is as a whole set at an inclination to the horizontal, being inclined upwardly in a direction from front to rear of the shell or body of the boiler-check, and the portion of the partition-wall between the chamber *e* below and the chamber *f*, in which it is seated,

is correspondingly inclined. The opening through which this valve and seat can be reached (closed by the cap or plug *k*⁶) is formed in the front wall of the shell at a corresponding inclination to and in axial alignment with the seat *k*⁵. By thus arranging the parts access may be had at any time to the intermediate valve, notwithstanding the fact that the chamber in which it is located is interposed between the primary chamber *e* below and the check-valve chamber *g* above.

Both top chambers *g* communicate through separate openings with delivery-chamber *h*, formed in the casting or valve-body, and each opening is controlled by its own stop-valve *m*, as indicated more plainly in Fig. 4, so that either half of the double check can be shut off from the boiler without interfering with the free communications of the other half.

Each stop-valve *m* is of the usual bevel-seated screw-spindle type and needs no further description. It is of course provided with the usual operating-handle on the outer end of its spindle, as indicated in Fig. 4.

The check-body is attached to the back head of the boiler by means of the flange *n*, surrounding the boiler end of delivery-chamber *h* and provided with bolt-holes *n*', through which pass bolts screwed into a flange which is riveted to the boiler in the usual and well-known manner.

In practice the operation of the device will be as follows: With valves *m* open and the injector in operation, the water pressed into the check-body by the injectors will open successively valves *k* and *l* and pass through chambers *e*, *f*, *g*, and *h* into the boiler. When the operation of either injector is stopped, back pressure from the boiler will automatically close the valves *l* and *k* appropriate to it and prevent a backflow of the water from the boiler through the half of the double boiler-check.

Both valves *k* and *l* may be constructed in equally substantial and strong manner, so that when either one is out of order from any cause the other will perform the functions of a boiler check-valve, which the ordinary, and necessarily small and weak, valve in the injector-body could not perform. The latter valve may therefore be dispensed with and all annoyances resulting from its necessarily unsatisfactory construction, location, and operation avoided. Placing both valves *k* and *l* into the same body also makes it necessary to employ a detached and independent valve in place of valve *k*, which method has heretofore been resorted to occasionally when conditions of space have permitted it. This possibility of dispensing with an independent valve greatly simplifies matters, as an independent valve would require two additional joints in the pipe between injector

and boiler-check for each side or half of the check—altogether, therefore, four additional joints—which fact would cause multiplication of parts, largely increased expense in the installation of the boiler-feeding apparatus, and create opportunity for leaks in these extra joints, and thereby increase the cost of maintenance. I avoid all this by placing all valves which are necessary in connection with the proper feeding arrangement of a locomotive-boiler in a single casting, thereby reducing the number of parts, the cost of arrangement, and the cost of its maintenance in good order to the lowest possible limit.

Should it be necessary to examine or remove either one of the valves *k* or *l* for repairs with steam in the boiler, this can be accomplished by closing either one or the other of stop-valves *m*, as the case may be, thus shutting off communication between the boiler and the various valve-chambers in that half of the check-body to which the stop-valve pertains.

While I have described and illustrated only the preferred form of my invention, and particularly its application to boiler-checks located on the back head of the boiler, it is obvious that the invention may be applied to boiler-checks placed on the side of the boiler and that modifications in the construction of the check-body and of the different valves may be made without departing from the nature and spirit of my invention.

In conclusion I state that I do not claim, broadly, a double boiler check-valve in which the shell is provided with a plurality of independent feed-water passages and a delivery bore or chamber common to said passages in combination with checks automatically con-

trolling said passages, respectively, and a separate and distinct stop-valve for controlling communication between each passage and the delivery bore or chamber; but

What I claim herein as new, and desire to secure by Letters Patent, is as follows:

1. In a double boiler check-valve, a valve-body divided vertically into two distinct and separate series of three superposed communicating chambers—a primary chamber below, an intermediate chamber and a check-valve chamber above—a check-valve in the intermediate chamber accessible through a cap-closed lateral opening in the walls of said chamber, a check-valve in the check-valve chamber accessible through a cap-closed opening in the top of the valve-body, a delivery-chamber common to and communicating with the check-valve chambers of each series, and a separate stop-valve for controlling communication between the delivery-chamber and each check-valve chamber, substantially as set forth.

2. In a boiler check-valve having a shell provided with check-controlled superposed communicating chambers *e*, *f*, *g* as described, an inclined valve-seat *k* in the intermediate chamber *f*, a check-valve *k*, and a correspondingly-inclined cap-closed lateral opening in the wall of the shell in substantially axial alignment with said valve-seat, substantially as and for the purposes hereinbefore set forth.

In testimony whereof I affix my signature in presence of two witnesses.

LEOPOLD KASSANDER.
